(57) **CLAIM**

The ornamental design for a photosensitive drum unit, as shown and described.

DESCRIPTION

FIG. 1 is a front view of a photosensitive drum unit;

FIG. 2 is a top view thereof;

FIG. 3 is a right-side view thereof;

FIG. 4 is a left-side view thereof;

FIG. 5 is a rear view thereof;

FIG. 6 is a bottom view thereof;

FIG. 7 is a perspective view thereof; and,

FIG. 8 is another perspective view thereof.

The broken line showing is for illustrative purposes only and forms no part of the claimed design.
